UNITED STATES PATENT OFFICE.

GEORGE W. CAMPBELL, OF FORT LARAMIE, WYOMING.

FOLDING SHOEBRUSH.

Application filed August 25, 1920. Serial No. 405,799.

To all whom it may concern:

Be it known that I, GEORGE W. CAMPBELL, a citizen of the United States, residing at Fort Laramie, in the county of Goshen and State of Wyoming, have invented certain new and useful Improvements in Folding Shoebrushes, of which the following is a specification.

This invention relates to new and useful 10 improvements in shoe brushes and more particularly to that type which provides a container for shoe polish and shoe cleaning implements, the primary object of the invention being to provide a device of this character which is exceedingly convenient, compact and thus it obviates the soiling of the user's hands when polishing shoes.

Another important object of the invention is to provide a brush or polisher of the present 20 type consisting of a body portion which is adapted to contain a can or cans of shoe polish, and also embodying a cover hinged to the body portion and to which is fastened the cover of the can of shoe polish whereby 25 when the cover of the brush is closed, the can of shoe polish is also closed by its cover to prevent the polish from becoming dry when the device is not in use.

Another object of the invention is to provide 30 a device of the above character including a body portion and a cover or closure, both of which are provided with corresponding pockets into which fit a can of polish and a closure therefor, the can and closure therefor being so arranged relative to the pockets and to the body portion and cover of the brush that when the brush is closed, the can of polish is also properly closed by its cover to preclude the admission of air thereto.

Still another object of the invention is to provide 40 a brush including a body portion having a handle extending therefrom and a polish receiving pocket in the body portion which communicates with an implement receiving pocket provided in the handle whereby a pocket or recess of sufficient size is provided to receive therein a polish dauber.

Other objects and advantages of the invention 50 will become apparent during the course of the following description.

In the accompanying drawings forming a part of the application and wherein like numerals are employed to designate like 55 parts throughout the several views

Figure 1 is a top plan of the invention.

Figure 2 is a plan of the invention in an open position.

Figure 3 is a side elevation of the invention in a closed position, parts thereof being 60 broken away to disclose the interior construction, and

Figure 4 is a transverse section taken on the line 4—4 of Figure 3.

Referring to the drawings wherein for the 65 purpose of illustration is shown the preferred embodiment of the invention, the numeral 1 designates the brush or polisher in its entirety and which is, in the present instance, formed from a block of wood to 70 provide a handle and an enlarged head 3. Both the handle and the head are divided longitudinally to provide a pair of similar sections which are hinged together along one longitudinal edge of the head by hinges 75 indicated at 4. For the purpose of distinction, I will term one section 5 as the body portion of the brush, while the other section 6 will be termed the cover.

In the inner faces of both the body portion and cover, I provide a pair of spaced 80 circular recesses or pockets 7, the pairs of pockets corresponding in shape and adapted to register when the cover is closed upon the body portion. The pockets 7 in the body 85 portion are adapted to snugly receive cans 8 of shoe polish or paste, preferably of different colors and it will be seen by referring to Figures 2 and 4 that the upper portion of the pockets 7 in the body portion are larger 90 in circumference than the cans of shoe paste to provide annular channels surrounding the upper portions of the cans of paste. It will also be noted that the upper edges of the cans 8 extend beyond or above the inner 95 surface of the body portion for a purpose which will appear.

Within the pockets 7 of the cover 6 I secure 100 by means of tacks or other suitable fastening means 9 the covers 10 of the cans of 105 polish. The edges of the covers 10 project beyond the inner face of the cover 6, whereby they may surround their respective cans 8 of polish and fit within the annular recesses or channels formed by enlarging the upper ends of the pockets 7 within the body portion 5. Consequently, it will be seen that when the cover 6 is swung upon the hinges 4 to dispose its inner face against the body portion 5, that the covers 10 of the 110 polish cans will fit properly upon the cans of polish to preclude the admission of air

thereinto. Of course, it will be obvious that only one pocket may be provided in the body portion for receiving a single can of polish while a corresponding pocket is formed in the cover 6 and that more than two cans of polish may be used in conjunction with larger brushes.

In the body portion 5, there is a recess 11 which communicates with a pair of pockets 7 to accommodate therein the cover lifting means ordinarily provided upon cans of shoe paste. Both the body portion and cover are provided with a longitudinally extending pocket or recess 13 the pocket in the handle carried by the body portion extending the full length of the handle while the pocket in the cover portion extends only a slight distance thereinto as shown clearly in Figures 2 and 3. It is obvious the recess 13 carried in the body portion is provided with oppositely disposed cut out portions 14 of sufficient size to permit of the user's fingers obtaining a grip upon the handle of a shoe dauber 15. A recess or dauber receiving pocket 16 is provided in both the body portion 5 and cover 6 and communicates with the pocket in the handle and the adjacent pocket for receiving either the can or its cover and these pockets 16 provide sufficient space for the head of the dauber to be received therein when the cover is closed upon the body portion.

For retaining the cover 6 upon the body portion when the brush is being used, a hook 17 is pivotally connected to the side of the body portion opposite that side to which the hinges are connected and an eyelet 18 is secured to the corresponding face of the cover.

As shown in Figure 3, the head of the brush is enlarged to provide shoulders at the juncture of the handle and head of the brush whereby the corresponding ends of felt 20 and sheepskin 21 may be fastened to the shoulders 19 by nails 22 or other fastening elements. It will be noted that the felt 20 is secured upon the outer face of the cover, while the sheepskin 21 is secured to the outer face of the body portion 5. The opposite ends of both materials are fastened by nails 22 to the outer ends of the cover and body portion.

From the foregoing description, it will be seen that an exceedingly handy and neat article has been provided, and when it is desired to clean the shoes, the hook 17 is unlatched whereby the cover 6 may be swung back from the body portion 5. At the same

time, due to the fact that the covers of the polish cans are secured to the cover, they are removed from their respective cans of polish 8. Consequently, as soon as the brush has been opened, the dauber 15 which may be provided at its handle end with a suitable scraper is lifted from its pocket and used in the well known manner. After the polish or paste has been applied, the dauber is replaced in its pocket and the sections of the brush are closed and locked by the hook 17 whereupon the handle 2 of the brush may be grasped and the shoes polished by rubbing the felt and sheepskin over the paste applied to the shoes. Of course, it will be obvious that bristles may be applied to either the outer face of the body portion or the cover in place of the felt or sheepskin.

The foregoing description and the accompanying drawings have reference to the preferred or approved embodiment of my invention. It is to be understood however that such changes may be made in construction and arrangement of parts, materials, dimensions, etc., as may prove expedient and fall within the scope of the appended claim.

Having thus fully described my invention, what I claim as new and desire to secure by Letters Patent is:

A blacking set comprising a two part casing, each part consisting of an elongated body having a complemental handle portion extending longitudinally from one end thereof, said two parts being hingedly connected together whereby the handle portions align and contact when the parts are arranged in closed position, one part having a recess in its face which registers with a corresponding recess in the face of the other part to provide a chamber to receive a can of polish therein, one of said parts having an instrument receiving recess therein communicating with its first named recess and extending longitudinally in its handle portion, and the handle portion of the other part being adapted to contact with an instrument received in the recess of said handle portion to prevent movement or vibration of the instrument when the two parts are closed.

In testimony whereof I affix my signature in presence of two witnesses.

GEORGE W. CAMPBELL.
